REUSABLE BUNDLING STRAP

George Geisinger, Elizabeth, N.J., assignor to The Thomas & Betts Co., Elizabeth, N.J., a corporation of New Jersey

Filed Apr. 11, 1966, Ser. No. 1,827

Term of patent 14 years

(Cl. 58—2)

FIG. 1 is a side perspective view of a reusable bundling strap showing my new design, the strap is shown broken away for convenience of illustration;

FIG. 2 is a bottom plan view thereof on a reduced scale;

FIG. 3 is a sectional view taken on the line 3—3 of FIG. 2, shown on a larger scale;

FIG. 4 is a front perspective view of my design as it appears in use prior to reversing the tail end portion through the head portion;

FIG. 5 is a front perspective view thereof in final position; and

FIG. 6 is a sectional view through the looped strap portion thereof, shown enlarged.

I claim:

The ornamental design for a reusable bundling strap, as shown and described.
